UNITED STATES PATENT OFFICE.

ERNST OSCAR NEBEL, OF PHILADELPHIA, PENNSYLVANIA.

DESIGN FOR A STOCKING.

Application filed May 26, 1928. Serial No. 26,869. Term of patent 7 years.

To all whom it may concern:

Be it known that I, ERNST OSCAR NEBEL, a citizen of the United States, residing in Philadelphia, Pennsylvania, have invented a new, original, and ornamental Design for a Stocking, of which the following is a specification, reference being had to the accompanying drawing, of which—

Fig. 1 illustrates a stocking embodying my new design as viewed from one side thereof,

Fig. 2 illustrates the same stocking as viewed from the opposite side thereof; and Fig. 3 is a rear elevational view of the lower portion of the stocking shown in Figs. 1 and 2.

I claim:

The ornamental design for a stocking substantially as shown.

ERNST OSCAR NEBEL.
